MOBILE GUN MOUNT

Walter H. D'Ardenne, Jenkintown Manor, Weber Devore, Horsham Township, Montgomery County, Robert W. Wolf, Philadelphia, and Thomas E. Boyd, Melrose Park, Pa., assignors to Heintz Manufacturing Company, Philadelphia, Pa., a corporation of Pennsylvania

Application February 28, 1944, Serial No. 524,282

5 Claims. (Cl. 89—40)

1

This invention relates to gun mounts, and more particularly, to mounts for light rapid firing automatic cannon and the like. While the invention contemplates an all purpose mount, mounts constructed according to the invention are especially effective for anti-aircraft purposes, such as against dive bombers and strafing planes. It is a major object of the invention to provide such a mount.

Modern war is a war of movement and consequently a mount should be capable of being easily and quickly transported from one place to another and readily positioned for firing. The present invention has for another object the provision of a mount which can be so transported.

Mounts constructed in accordance with the invention are provided with tripod legs, two of which are adapted to support wheels. When the mount is positioned for firing, the wheels are disposed off the ground and out of the way (or removed altogether) with the spade feet of the legs disposed solidly in the ground. When it is desired to transport the mount, these legs may be adjusted so that the wheels support the mount and the spade feet are swung to a position above the ground. The third leg of the mount is designed as a towing leg and may be provided with drawing handles and a lunette. It is a further object of the invention to provide such a construction.

Rapid firing automatic cannon of the light type as now employed are of two different designs, one of which is known as the Oerlikon 20 mm. and the other of which is known as the Hispano 20 mm. These cannon have different mounting points. It is, of course, highly desirable to provide a mount which can employ either of these two guns. Another object of the present invention resides in the provision of means for cradling either of these two types of guns. This means is comprised of two different cradles, each of which may readily be substituted for the other.

It is important that mounts for light cannon, machine guns and the like, be properly proportioned and designed to compensate as nearly as possible for recoil movement, vibration and other factors which otherwise would seriously affect the accuracy of fire. It is an important object of the invention to provide a mount which accomplishes these aims.

The invention, for a further object, provides a mount which may be fired in all positions of traverse and in elevation and depression to about plus 85° to minus 10°, the gunner at all times remaining in erect standing position in which he is protected by an armor plate shield.

2

Other objects of the invention reside in the provision of an improved armor plate shield construction, sighting means, means for securing the mount to a permanent or semi-permanent foundation, and in the provision of a mount requiring no equilibrator springs or counter-balance weights.

These and other objects of the invention will become more apparent from the following description and claims when read on the accompanying drawings in which:

Figure 1 is a side elevation of a gun mount constructed in accordance with the invention, the mount being shown in firing position.

Figure 2 is a top plan view.

Figure 40 is a plan view of the same recoil mechanism.

Figure 41 is a view taken on the line 41—41 of Figure 39, and

Figure 42 is a front end elevation of the forward block of the recoil mechanism with the recoil spring and rod removed.

With reference first to the general views Figures 1, 2 and 3, the mount has a pedestal standard 10 of tubular construction provided at its lower end with a base plate 11. Welded to the standard and the base plate are three sockets for detachably retaining the legs 15, 16 and 17. These sockets are spaced 120° apart about the standard, two of the sockets being shown at 12 and 14 in Figs. 1, 3, and 6.

In its upper end portion the pedestal standard has a cylindrical support member 18 mounted therein for rotation about the vertical axis of the pedestal standard. The cylindrical support member 18 is adapted at its upper end to support detachably a cradle yoke 19. The support member 18 may be locked in any of its positions of rotation by turning the handle 20. The particular manner in which the support member 18 is mounted for rotation and also the manner in which it may be locked form no specific feature of this application. A similar arrangement is illustrated and described in copending application, Serial No. 465,616, filed November 14, 1942, now Patent No. 2,415,340, in which several of us are named as inventors. It should suffice to point out here that the support is rotatable, may be locked by operation of the handle 20, and detachably supports the cradle yoke 19.

The arms 21 and 22 of the cradle yoke 19 are provided with laterally extending trunnion pins 23 and 24 (see Figures 2 and 17) which pass

through bearings in the two cradle plates 25 and 26 of the gun cradle. The trunnion pins form a horizontal pivot axis on which the gun cradle may pivot in a vertical plane.

The gun cradle supports the gun 27 (in this instance shown as a Hispano 20 mm. rapid firing cannon). The gun has a detachable ammunition chest 28. The manner in which the gun is supported in the gun cradle will be described hereinafter.

The rear end of the gun cradle carries a trigger mechanism for firing the gun. The trigger mechanism is comprised of a tubular framework 29, secured to the cradle plates 25 and 26 by bolts or the like, and includes a pair of tubular members 30 and 31 which are inclined forwardly and upwardly. These members carry lugs 32, three on each member, which lugs have the handle grips 33, 34, 35 and 36, 37 and 38 rotatably mounted thereon.

The handle grips 36, 37, 38 carried by the lugs 32 on the inclined tubular member 31 (for the gunner's left hand) are mounted on arms such as 39, which are pivotally joined to a connecting bar 42 so that turning any one of these handle grips will cause the connecting bar 42 to move downwardly. An actuating rod 43 joins the connecting bar 42 to mechanism carried by the cradle plate 26, and which engages the detent mechanism of the gun. This mechanism will be presently described. It should be noted here, however, that turning of any of the three handle grips 36, 37 and 38, will, through its corresponding arm 39, the connecting bar 42, the actuating rod 43 and said mechanism, actuate the detent on the gun and thus fire the gun. It is obvious that the number of handle grips may be varied. In some instances, two will suffice. In others, four or even more will be employed.

The rear ends of the cradle plates also have a U-shaped safety member 44 secured thereto to furnish extra protection to the gunner in the event the rear end of the gun should blow out when the gun is fired.

The mount embodies an armor plate shield 45 (see also Figures 4 and 5), the central portion of which is substantially vertical, while the upper and lower portions are inclined upwardly as clearly shown in Figure 1. The shield is rendered substantially rigid by the tubular braces 46, 47 and 48, 49, which are welded thereto, and by two reinforcing ribs or plates 50 and 51, disposed in parallel vertical planes on the forward surface of the shield on either side of the opening 52 (Figure 5) through which the gun cradle and gun extend. The plates 50 and 51 preferably are welded to the shield.

These reinforcing plates 50 and 51 are provided with aligned openings reinforced by bearings 53 and 54 in which the ends of the trunnion pins 23 and 24 may be disposed to support the shield on the cradle yoke 19. The rearward underside of the shield carries a pair of lugs 55, 56 which carry rotatable threaded bolts 57 and, having handles such as 58. These bolts are adapted to be threaded in holes in opposite sides of the cradle yoke to secure the shield rigidly to the yoke. It will be understood, however, that since the yoke is, in turn, carried by the rotatable support member 18, the shield 45 will rotate with the latter. The shield thus rotates with the support member 18 when the gun is moved in traverse. The shield, however, being rigid with the yoke, does not move with the gun cradle and gun when the gun is elevated or depressed. The opening 52

in the shield is sufficiently large to permit full elevation and depression.

The shield 45 is comprised of two separable portions, an upper shield portion 59 and a lower shield portion 60 disposed at the lower edge of the portion 59. The lower portion 60 includes a bucket-shaped ammunition chest container 61 provided with a lid 62 hinged at 63 on pins carried by lugs on the lower edge of the upper shield portion 59. The lid 62 may be secured in closed position by the releasable fastener 64.

This lower shield portion 60 is detachably secured in position to rotate with the yoke 19 by means of a bracket 65 which is comprised of two side members, the forward edges of which are welded to the ammunition chest container 61. These side members extend rearwardly inwardly and upwardly and their uppermost portions are joined together (as an inverted U). At the position of juncture, there is provided an integral, rearwardly and downwardly projecting hook 68 which engages over the edge of the notch 69 (Figures 16, 17) formed in the yoke 19.

The bracket 65, or the container 61, as shown, carries a lug 73 provided with a vertical hole in which is threaded a bolt 71. The bolt is provided with a handle 72 at its lower end. The rotatable support member 18 is provided with a lateral block 70. The bolt 71 is adapted when turned to extend through the lug 73 and to engage the under surface of the block 70, thus securely clamping the lower shield portion 60 in place.

The ammunition chest container 61 forming part of the lower shield portion 60 may be used for storing extra ammunition chests, such as the one 28 shown in dotted lines as on the gun in Fig. 1. The container 61 may be provided with side handles such as 74 to facilitate lifting the container and in holding the same when the bucket is being attached, detached or transported.

The mount may include an improved sighting arrangement which can be understood from an examination of Figs. 1, 2 and 3. This sighting arrangement operates on the principle of a varying parallelogram comprising two forked members 75 and 76, the lower double ends of each being provided with lugs which are engaged in holes in the cradle side plates 25, 26 so as to be pivoted to the cradle side plates. The forked members are forced apart when they are being assembled in place. These forked members 75 and 76 form two sides of the parallelogram and the cradle side plates and the bar 77 (pivotally connecting the upper ends of the members 75 and 76) form the other two sides.

The connecting bar 77 is adapted to support the sight bar 78 at two points. One is through the yoke 79 (rigid with the connecting bar) to which the sight bar is pivotally mounted. The other, 80, is intermediate of the connecting bar 77. This latter connection 80 is normally rigid but since it includes the threaded bolt and lock-nut arrangement 81 shown, it is apparent that the relative position of the connecting bar 77 and the forward end of the sight bar 78 may be varied.

The sight bar 78 rigidly carries a forward sight ring 82 and also a much smaller rear sight ring 83. The rear end of the sight bar 78 has a rocker arm element 84 pivoted thereto, the end of which is formed as a snap catch 85 for detachably engaging the central part of a bail 86 which is swingably mounted at its ends in lugs 87 carried by the underside of the armor plate shield.

Having now described certain general features

of the mount, it is believed to be desirable to describe several of the specific mechanical details which also form important features of the invention.

As previously indicated, the mount is provided with three legs 15, 16 and 17 which are adapted to fit into the three leg sockets, two of which are shown at 12 and 14 secured near the base plate 11 of the pedestal standard 10. Figs. 1 and 2 show the legs disposed as a tripod to support the mount when it is being fired. Two of the legs 15 and 16 are provided with wheel arrangements which may be manually changed so that the wheels on these legs support the mount for transportation. The remaining leg 17 is provided with a handle arrangement for pulling the mount by hand, and also with a lunette by which the mount can be attached to a motor vehicle.

Each of the legs is preferably constructed of tubular metal, the outer ends of which are provided with spade grips, such as 88.

The inner ends of the legs are releasably clamped in the aforementioned sockets by means of a threaded bolt 89 provided with two clamping blocks 90 and 91, having arcuate upper surfaces (see Figure 6). The bolt passes laterally through the socket and is provided with an operating handle 92 disposed on the outside of the socket. When the handle 92 is turned, the clamping blocks 90 and 91 will move toward each other relatively and clamp the leg between them and the upper inner surface of the socket.

Each leg near its inner end is also provided with two holes disposed on radii at right angles to each other. Such holes, 40 and 93, are shown in Figure 7. When the legs are disposed in one of their operative positions, one of the holes in each leg is adapted to be engaged by a spring pressed plunger 94 provided with a handle 95 (see Figures 7 and 8 in particular). The plunger 94 provides a positive lock for retaining the leg within the socket. The locking action is released merely by pulling out the handle 95.

When the wheel legs are employed for transportation, they are inserted in their sockets in a position turned 90° to that shown in Figures 1 and 2. The other hole 40 (Fig. 7) near the inner end of each leg is then adapted to be engaged by the plunger 94.

For purposes of permitting an easy entering of each leg for each of its two positions, the legs are provided with studs such as 96 which respectively engage either in the slots 97, in the top of the leg sockets, or in the slots 98 in the sides of the leg sockets.

The legs 15 and 16 carry wheels 99 and 100, and these legs are provided with a joint so that they may assume either a straight position (Figures 1, 2, 9 and 10) or an angled position (Figures 3 and 11). In the latter position the wheels 99 and 100 will support the mount for transporting it from place to place.

With reference to Figures 9, 10, 11 and 12, the two wheel legs are each comprised of two sections 101 and 102. The outer section 101 at its joining end is provided with a rigid block member 103 having a central tongue 104 of less width than the block proper. The inner section 102 at its joining end is also provided with a block 105 having a central slot in which the tongue 104 is disposed. A pivot pin 106 passes through the block 105 and tongue 104 to provide a pivot joint. The outer surface of the block 105 is inclined as at 107 (on each side of the slot) and these inclined surfaces engage complementary

inclined surfaces 108 on the block 103, when the two sections are in alignment as shown in Figures 9 and 10.

It will be apparent that the pivoting arrangement will permit the two leg sections also to move to the position shown in Figure 11. In this position each wheel axle 109 is disposed on an angle and the wheel carried thereby will be in the position shown in Figure 3. Each wheel axle 109 is secured in a transverse bore which passes through the block 103. The end of each axle 109 is provided with a nut 110 and a locking pin 111 is adapted to pass through both the block 103 and the axle 109.

Means are provided for locking the two leg sections in either of their two positions. The block 105 is provided with a transverse hole in which is disposed a locking pin or rod 112 having a cut-away notch 113 (see Figure 12). One protruding end of the rod 112 is provided with a handle 114 and a nut 115. The other protruding end has two spaced collars 116 and 117 and a handle 118. Between collars 116 and 117 lies a rod portion having two parallel flat sides 117a and rounded portions 117b. The distance between flat sides 117a is substantially smaller than the distance between rounded sides 117b. When the rod 112 is turned to one position, the rod will permit the tongue 104 to pivot, since the arced edge 119 of the tongue 104 does not engage the rod 112 because of the notch 113. However, the rod when turned will engage the arced edge 119 of the tongue 104 and thus lock the two leg sections against pivoting movement. The block 105 also carries a pin 120 extending from one side thereof. A U-shaped spring member 121 is disposed over the pin and extends downwardly with its lower ends disposed between the two collars 116 and 117 of the locking rod 112 where they bear against flat sides 117a of the rod (as shown in Figure 11). Inasmuch as the arms of the U-shaped spring member 121 are placed under tension when rod 112 is rotated from the locking position in which it is shown in Fig. 11 wherein the arms of the spring contact the flat sides 117a of the rod portion between collars 116 and 117, spring member 121 tends to maintain rod 112 in the locking position in which it is shown in Figs. 9 through 11. A shroud 122 secured by a nut is provided on the pin 120 to keep the spring from slipping off of the pin.

It will be noted that the tongue 104 on block 103 is provided with a cut-out 123 which engages the locking rod or pin 112 when the two sections are in the position shown in Figure 11.

With reference to Figures 3, 13, 14 and 15, the leg 17 is the towing leg and is provided with a lunette ring 124 welded to the side handles 125 formed of a rod of bail shape rigidly welded to the upper surface of the spade foot and also to the under surface of the leg at 126, at which latter point it passes through the lug 127 which depends from the leg.

The underside of the leg is also provided with manual drawing means which is comprised of double bars 128, 129 pivoted at 130 so as to be capable of swinging either to the drawing position (shown in full lines) in which the handle bar 131 may be manually grasped, or to an operative position (dotted lines). The double bars 128, 129 may be releasably locked in either of such positions by means of a spring urged plunger 132 (Figure 15) carried thereby and which is adapted to engage selectively in a hole 133 in the spade foot 88 or in a hole 134 in the lug 127.

As shown in Figure 15, the plunger 132 is mounted in a cylinder 135 threaded in an opening in the bar 129. The piston is connected by a rod 136 to a knob handle 137. The plunger may be disengaged from locking position (shown) merely by pulling on the knob handle 137 against the action of the coil spring 138.

The gun cradle is illustrated in Figures 1, 2, 16 and 17. It is comprised of the two sheet metal side plates 25 and 26, some of the edges of which are preferably flanged outwardly for strength. These cradle plates are held in parallel spaced relation by a forward block 139 and an intermediate block 140, to which the side plates are bolted. At the rear the cradle plates are also secured by the U-shaped safety member 44 which is bolted thereto.

As previously referred to in a general manner, the cradle yoke 19 has two arms 21 and 22 provided with aligned openings for the trunnion pins 23, 24 which pass through openings in the cradle plates and into the arms 141 and 142 rigid with the intermediate block 140, to support the gun cradle for vertical pivoting movement.

Means are provided to lock the gun cradle in any of its positions of pivoting movement. As seen in Figures 1 and 16, the cradle plates have an arcuate lower edge 143 at the center. Clamping blocks such as 144, mounted on the shaft 145, are disposed adjacent to the cradle plates overlapping the arcuate edge 143. The shaft 145 is provided with an operating handle 146. (See Fig. 1.) When the handle 146 is turned in one direction it will rotate the shaft 145 and cause the clamping blocks 144 to engage the surfaces of the cradle plates, thus locking them against pivoting movement about the trunnion pins.

If desired, the yoke 19 may be provided with a hole for a pin 9 adapted to enter a hole in the cradle plate 143 to lock the cradle and gun in horizontal firing position.

The gun is supported in the gun cradle in the following manner. The gun is provided at its central portion with a flat underside. On the sides of the gun adjacent this surface are longitudinal grooves. With reference to Figure 18, the flat under surface of the gun is supported by the upper surface 147 of the intermediate block 140, while the longitudinal ribs 148, 149 on the block engage in the grooves in the gun to which reference has been made. The forward block 139 (see Figures 16, 17 and 19) is provided with a threaded opening 150. The gun is provided with a sleeve adapter 151 (Figure 1) and the gun is passed through the threaded opening 150 with the adapter 151 secured in this opening.

Reference has already been made to the manner in which the gun is fired by actuating any of the handle grips 36, 37 or 38 (Figure 2). The details of the firing mechanism on the mount now require recitation.

The connecting bar 42 (Figures 1, 20 and 21) when moved downwardly by actuation of the handle grips moves the actuating rod 43 downwardly. Figures 20 and 21 show how this rod 43 is pivotally joined as at 152 to the arm 153 of a double armed rocker. The rocker is hinged as at 155 on a bracket 156 secured to the cradle plate 26.

The other arm 157 of the double armed rocker 70 is blunt ended and engages the upper surface of a bar 158, one end of which is pivoted at 159 to the bracket 156. The other end of the bar is provided with a notch which engages the detent 160 of the gun just above the nut 161.

When the actuating rod 43 moves downwardly,

as described, it will move arm 153 of the rocker 154 downwardly, thus causing the blunt end of the other arm 157 to press downwardly against the pivoted bar 158. This results in drawing downwardly on the detent 160 of the gun and firing the latter.

While so far in the description of the invention the mount has been described as a tripod mount capable of conversion to a wheeled mount for transporting purposes, the mount can also be used with a semi-permanent adapter base which may be bolted or otherwise secured to the deck of a ship, a concrete foundation, the floor of a vehicle, or the like. Such an adapter base is shown, for example, in Figure 6. It is comprised of a circular base plate 162 which may be secured to a foundation or the like by any suitable means, a central upright portion 163, a circular top plate 164, and a plurality of reinforcing webs 165, all welded together in a unit. The base plate 11 of the pedestal of the mount may be bolted as at 166 to the circular top plate 164 of the adapter. Alternately, it may be secured to the circular top plate of the adapter by means of quick acting clamps or the like. Such clamps, for example, are illustrated and described in copending application, Serial No. 465,616, filed November 14, 1942, now Patent No. 2,415,340, issued February 4, 1947, to which reference has heretofore been made. It is, of course, not necessary to employ the legs 15, 16, 17 of the tripod support when the adapter just described is in use.

In the statement of the objects of the invention in the early part of this specification, it was stated that an important object of the invention was its adaptation for use with either the 20 mm. Hispano cannon or the 20 mm. Oerlikon cannon. This interchangeable feature, is simply accomplished by substituting a different gun cradle for the one heretofore described.

The gun cradle for guns of the Oerlikon type is illustrated in Figures 22, 23, 24, 25, 26 and 27. The cradle plates 167, 168 thereof are substantially of the same shape and dimensions of the cradle plates heretofore described as for use with guns of the Hispano type. The cradle plates 167 and 168 are held in spaced parallel relationship by three special blocks 169, 170 and 171, which will be referred to, respectively, as the forward, intermediate and rear blocks.

The rear block 171 (see Figures 22, 23 and 26) is provided with a longitudinal cut-out 172, the side edges of which are provided with undercut longitudinal grooves 173 and 174. These grooves are adapted to engage ribs (not shown) on the sides of the gun near the rear end thereof.

The intermediate block 170 (see Figures 22, 23, 24 and 27) is also provided with a longitudinal cut-out 175 and undercut grooves 176 and 177 which are adapted to engage ribs on the side of the gun. The undersurface of the gun 154 at the point of engagement with the intermediate block 170 is provided with a hole 178. This hole 178 is adapted to engage a spring pressed plunger 179.

In mounting the gun in the cradle, the knob handle 180 (see Figures 22, 24 and 27) is loosened. When the gun is disposed in its proper position, the plunger 179 will snap into the hole 178. The knob handle 180 is then tightened on its threaded mounting and firmly presses the plunger in the hole and against the under surface of the gun. This action effects a clamping of the gun to the block as the ribs on the gun press firmly against the upper surfaces of the grooves 176 and 177.

The intermediate block 170 is also provided

on its side edges with longitudinal polysided grooves 181 and 182. Complementary shaped elements 183 and 184 engage in said grooves. These elements 183 and 184 have upstanding arms 185 and 186 through which the trunnion pins 23 and 24 pass. A bolt, such as 187, extends through the elements 183 and 184, the intermediate block 170 and the cradle plates 167 and 168 to hold them all securely together.

10 The front block 169 (Figures 22, 23 and 25) is not engaged by any part of the gun. It is bolted to the cradle plates and serves a dual purpose, first, to secure the cradle plates in spaced parallel relationship, and secondly, as a counter-weight to balance the gun properly in the mount. The Hispano type gun is longer and heavier at the front than the Oerlikon type and consequently a counterbalance weight is highly desirable when the mount is used for Oerlikon type guns. This front block 169 obviously suits this purpose. As shown in Figures 22 and 23, the weight effect of the front block 169 may be adjusted and varied by adding further weight elements such as 188 and 189 which may be removably secured to the front block 169 by means of a bolt 190 or the like.

25 In guns of the Oerlikon type, the firing is accomplished by moving a laterally extending pin rearwardly of the gun. Consequently, the trigger actuating mechanism used with the gun cradle for Oerlikon type guns differs from that heretofore described. Instead, it may be as shown in Figure 22 as merely comprising a bar 191 secured to the lower end of the connecting bar 42. The bar 191 has an engaging surface 192 which bears against the firing lug 193 on the gun. When the connecting bar 42 is moved downwardly to the left (Figure 22), the engaging surface 192 of the bar 191 will move the firing lug 193 rearwardly of the gun and thus fire the latter.

30 40 In Figures 29 to 31, inclusive, an alternate form of towing leg is illustrated. In this form the side handles are also comprised of a rod 201 in the form of a bail welded or otherwise secured to the 45 towing leg 202. The front end of the towing leg has a forwardly extending bracket 203 welded thereto. A lunette 204 is welded to the bracket 203.

45 The double bars 205, 206 in this instance are 50 secured to the upper side of the towing leg. They are pivoted as at 207 to the upstanding lug 208 (see Figure 30). When in their forward drawing position as shown in full lines in Figures 28 and 29, the double bars 205, 206 are locked in 55 such position by means of the spring pressed plunger 209 which is carried by the bar 205 and is adapted to enter an opening 210 in an upstanding lug 211 welded to the front of the leg. Figure 31 is a section taken through the plunger bars and lug.

60 Locking of the bars in inoperative position (shown in broken lines in Figures 28 and 29) is similarly effected, the spring pressed plunger 209 in this case engaging an opening 212 in a lug 213. 65 As in the other embodiment, a handle bar 214 is provided.

65 Figures 32 and 33 illustrate a modified form of 70 support for the sighting arrangement. In the other form of sighting arrangement (Figures 1, 2 and 3) the forked members 75 and 76 are assembled by forcing each laterally until the lateral lugs on their lower ends become disengaged from the holes in the cradle side plates. In the form shown in Figures 32 and 33, this action is facilitated by a toggle arrangement.

Briefly, the forked member is comprised of two tubular rods 215 and 216 which are welded at their top ends to a U-shaped piece 217. Intermediate their upper and lower ends the tubular rods are connected by the toggle mechanism comprised of the link 218 pivoted at 219 to a lug on the rod 215 and at its other end to the member 220 as at 221. The member 220 is pivoted to the rod 216 and is provided with a notched gripping portion 222.

The lower ends of the rods are threaded to receive the lug members 223 and 224. These lug members have four equally spaced lugs 225, any one of which may be positioned to engage the pivot opening in the cradle plates. It will be noted that the effective height of the forked rods can thus be adjusted.

In assembling the forked rods on the mount, the gripping portion 222 of the member 220 is manipulated upwardly to pivot the member 220 in a counter-clockwise movement. This causes the link 218 to straighten and forces the tubular rods 215, 216 apart so that the lugs 225 may be easily positioned for engagement within their pivot holes in the cradle plates.

A modified form of shield is shown in Figures 34 and 35. In this instance the shield 226 at its forward end terminates in a downwardly extending portion 227 which as will be noted is not provided with a bucket as in the previous embodiment.

As before, the shield is braced by tubular rods 228 and 229 and 230 and 231. Strengthening ribs 232 and 233 in this embodiment extend upwardly along the upper portion 234 of the shield and forwardly and downwardly to the point 235 to lend rigidity to the downwardly extending portion 227.

The shield is provided with an opening 236 for the gear cradle and gun, and also with a sighting opening 237. The shield is pivoted by means of the bearing member 238 in a manner similar to that previously described, and a lug 239 is provided similar to the lug 55 in Figure 1 for securing purposes.

It should be obvious that, if desired, the height of the shield may be less than shown in Figure 35.

A modified form of mounting for the wheel is shown in Figures 36, 37 and 38. In this instance the two wheel legs are each comprised of two sections, an inner section 241 and an outer section 242. Both sections are preferably of tubular steel. The inner section 241 is adapted for engagement in a leg socket such as 243 in the pedestal base. The socket 243 is provided with a notch 244 which receives a lug 245 on the upper surface of the leg. A spring pressed lug 246 carried by the socket 243, and provided with an operating knob 247 is adapted to engage in a hole in the upper surface of the inner section 241 near its inner end.

The outer end of the inner section 241 of the leg is provided with a block 248 which is slotted intermediate its upper and lower surfaces to receive a tongue 249 carried by the outer section 242 of the leg as will be described. The tongue 249 is pivotally mounted in the block 248 by a pivot pin 250.

The upper surface of the block 248 has an octagonally shaped member 251 welded thereto which member is provided with two bores 252 and 253 which cross at the center. These bores are adapted selectively to receive the axle 254 of the wheel 255. The axle 254 is held in place by

the bolt 255 threaded in the octagonally shaped member 251 to bear against the axle in a bore and provided with a knob handle 256 and a lock nut 257.

5 The outer edges of the block 243 (see Figure 37) are beveled as at 258 and are provided with rectangular notches such as 259.

The outer section 242 of the leg is provided with the tongue 249, as mentioned. Adjacent 10 the tongue 249, the outer section 242 of the leg is provided with a sleeve 260 which may slide longitudinally on the leg section and which is tensioned inwardly by the spring 261. The edge of the sleeve adjacent the tongue 249 is formed with rectangular projections 262 and 263 at the top and bottom, the edge being beveled from these projections toward the sides of the sleeve.

In the position shown in Figure 38 where the leg is positioned for firing, the projections 262 and 263 on the sleeve 260 engage in the notches 259 and hold the outer section 242 of the leg firmly. When it is desired to transport the mount the sleeve on each wheel leg is pulled outwardly against the action of the spring 261 (the lugs 264 facilitate this operation) and the projections 262 and 263 become disengaged from the notches 259 so that the outer section 242 of the leg may be pivoted to the side (see the top view, Figure 37). The outer section is held in such side position (off the ground) by the projections 262 and 263 which now engage notches such as 265 in lugs 266 carried on the side of the block 243. The wheels are then inserted as described.

In Figures 39, 40, 41 and 42 is illustrated a recoil arrangement which may be employed in the mount as described for guns of the Oerlikon type.

The cradle side plates 267 and 268 in this instance are provided with longitudinal bars 269 and 270. The facing surfaces of these bars are 40 stepped to provide guide tracks 271 and 272.

The intermediate block 273, to which the gun is secured in the manner previously described, has its side edges grooved to engage the guide tracks 271 and 272. The intermediate block 273 is provided with a transverse slot 274 through which extends the bolt 275. The slot is of a width considerably greater than the diameter of the bolt 275 and the arrangement is such that when the gun is fired, the block 273 may move for a limited distance in a longitudinal direction on the guide tracks 271 and 272.

The bars 269 and 270 securely support a second block 276 by means of the bolts 277 and the complementary shaped engaging surfaces of the bars 55 and the block as will be noted in Figure 42. These surfaces are separated by cushioning layers of "Fabrika" or the like (Figure 42).

The central portion of the block 276 is provided with a cylindrical bore 279. A recoil rod 280 extends through the bore 279. The rear end of the rod 280 enters an opening in the intermediate block 273 to which it is rigidly secured by means of the pin 281. Each end of the rod 280 is threaded to receive the adjustable collars 282 and 283. 60 Two other collars 284 and 285 are loosely disposed on the rod 280 on each side of the block 276. A recoil spring 286 is disposed on the rod 280 between the collars 285 and 283, and another recoil spring 287 of greater length is positioned 65 on the rod 280 between the collars 284 and 282.

70 The recoil device just described operates as follows: The gun, as mentioned, is secured to the intermediate block 273. When the gun is fired it kicks back (to the left in Figures 39 and 75 40). The intermediate block 273 will slide to the

left and since the rod 280 is rigid with this intermediate block 273, it will also move to the left against the action of the spring 286. The recoil mechanism is double acting and the rebound or return, after recoil, is cushioned by compressing the spring 287 as the rod 289 moves to the right to its original position.

It will be noted that the compression of each spring can be adjusted by varying the position of the threaded collars 282 and 283.

The gun mount illustrated and described is transported from place to place when assembled in the manner shown in Fig. 3. When it is desired to assemble the mount for firing, the outer sections 101 of the legs by which the wheel axles are supported are pivoted to the position shown in Figs. 1, 2 and 10 or in the alternative form to the position shown in Fig. 38. It will be noted that in this position the three legs support the mount securely on the ground for firing while the wheels are disposed upwardly where they are out of the way.

The gunner then removes the locking pin 9 and loosens handles 18 and 20 (Fig. 1). The mount is now ready for firing and the gunner grasps any one of the series of handle grips by which he may swing the gun in all positions of elevation, depression and traverse. It will be noted that the gun cradle, its yoke support and the shield all rotate with respect to the vertical support 10 and that consequently the gunner is protected by the shield during all positions of firing. Moreover, because of the particular firing arrangement in accordance with which the gunner may grasp different handle grips for different positions of elevation and depression, the mount may be fired in any position of elevation or depression while the gunner remains in standing position.

It is obvious that changes in the structural arrangement of the parts may be made within the scope of the invention which is only to be limited in accordance with the following claims.

We claim:

1. A mobile gun mount for light automatic fast firing cannon and the like, comprising, a vertical support for a gun cradle and shield, three legs the inner ends of which are detachably secured in the base of said support, two of said legs having pivoted joints intermediate their ends, means on said two legs for supporting wheels, means for securing said jointed legs selectively in straight position with their outer ends resting on the ground and with the wheel axes in upright position or in elbowed position in which their outer ends are positioned to the side and in a position out of the way of supporting wheels, the third leg comprising a towing leg. 50

2. A tripod mobile gun mount, one of the legs comprising a towing leg, the other two legs each being comprised of an inner portion and an outer portion pivoted together whereby the outer portion may be swung to the side, means on said outer section of each of said two legs for supporting an axle and a wheel, and means for lock- 65

ing the outer portion either in alignment with the inner portion when the gun mount is positioned for firing, or in side position when the mount is to be transported.

5. 3. A tripod mobile gun mount, one of the legs comprising a towing leg, the other two legs each being comprised of an inner portion and an outer portion pivoted together whereby the outer portion may be swung to the side, means on said outer section for supporting an axle and a wheel, and means for locking the outer portion either in alignment with the inner portion when the gun mount is positioned for firing, or in side position when the mount is to be transported, said locking means including locking surfaces carried by said outer portion, a movable member carried by said inner portion, and spring means urging said movable member into locking engagement with said locking surfaces carried by said outer portion.
10. 4. A gun mount for light automatic fast-firing cannon and the like, comprising a vertical support for a gun cradle and shield, three leg sockets carried by the base of said support, three legs adapted to be removably engaged in said sockets; two of said legs having pivotal joints intermediate their ends, wheel axles and wheels carried by said jointed legs, means for securing said jointed legs selectively in straight position with the feet resting on the ground and the wheels supported above the ground or in elbowed position with the wheels resting on the ground and the feet elevated therefrom, and means carried by the third leg for towing the mount when supported by said wheels.
15. 5. A mobile tripod gun mount, two of the legs having wheel means adapted to support the mount when being transported, the third leg comprising a towing leg, said towing leg having a lunette secured to its outer end, an arm pivotally secured on said towing leg, a pair of side handles on the free end of said arm, and means for locking said arm selectively in a stowed position against said towing leg and within the longitudinal limits of said leg or in drawing position in which the free end of the arm extends beyond the outer end of said leg.
